UNITED STATES PATENT OFFICE

2,456,756

SHOE TREE

Chester Tietig, Park Hills, Ky.

Application November 23, 1945, Serial No. 630,238

3 Claims. (Cl. 12—128.1)

1

This invention relates to a shoe tree adapted to be formed of sheet material. Preferably it is made of stamped steel or other metal, although it may be made of other high resilience material such as laminated plastic, for example, a canvas laminate, or it may be molded of strong resilient plastic alone. It may be formed of plastic covered metal or of plywood alone.

The object of the invention is to provide a shoe tree that is light, strong, springy and capable of exerting considerable force to straighten the shoe. A special modification is provided to exert a cam action to straighten stubborn shoes. It is a further object of the entire invention to provide a shoe tree that can be made substantially with one stroke of a punch press.

Referring now to the drawings,

Figure 1 is a plan view of a simple form of my shoe tree.

Figure 2 is also a plan view of a form having a narrowed shank.

Figure 3 is a side elevation of either Figure 1 or Figure 2.

Figure 4 is an "X-ray" view showing the tree being used in a shoe.

Figure 5 is a cross section taken on the line 5—5 of Figure 3, facing toward the toe.

Figure 6 is a fragmentary elevation showing a form having a bent shank and without a curl on the end of the shank.

Figure 7 is a plan view of a form having a middle rib of intermittent character.

Figure 8 is a side elevation of Figure 7.

Figure 9 is a cross section taken on the line 9—9 of Figure 8 facing toward the toe.

Figure 10 is an "X-ray" view showing the form of Figures 7, 8, and 9 in use in a shoe. The dotted lines indicate the shank after it has been forced down to accomplish a camming action.

Figure 11 is a side elevation (fragmentary) showing a modification of the middle channel.

In all forms 10 is the toe portion, which is hollow. 11 is a shank integral with the toe portion and extending from the top rear thereof, and 12 is a curled part of the shank which may or may not be present in any of the modifications. The function of the curl 12 is to prevent gouging of the interior of the shoe by the free end of the shank 11. Figure 6 shows a form of shank that already has the arcuate bend which the forms shown in Figures 1, 2 and 3 assume when used in a shoe, as in Figure 4. In Figure 6, the curl 12 has been omitted.

A depressed center channel 13 is a distinguishing feature of the forms shown in Figures 7 to

2

11 inclusive. It may be either interrupted by openings 14 or it may be of increasing depth toward the outer end of the shank 11 as shown in Figure 11. It extends preferably but not necessarily into the toe portion 10 as shown in Figure 9.

By the use of the interrupted channel, the shank is constrained to bend in preselected places, i. e., where there is no channel. This is shown clearly in Figure 10. Therefore, by pressing firmly on the highest one of such places in the arc of the shank 11, the direction of curvature can be reversed as shown by the dotted lines in Figure 10. A powerful camming action or toggle action is thereby obtained. The two rear portions of the rib lock against each other to transmit the push. In this way the same toggle effect is obtained that formerly required multi-piece hinged construction to make possible. A more expeditious result is therefore achieved by simpler mechanism. By the use of hollow toe caps the evaporation of perspiration from the shoe is facilitated.

In the form shown in Figure 11, the channel 25 serves to increase the strength of the spring shank 11 where extra resilience is most needed to extend the shoe. There is no interference with camming action if it is desired to employ the latter. However, a short shoe will not be as 30 suitable for camming as a shoe which is somewhat longer in relation to the length of the shoe tree. This statement applies also to the form shown in Figures 7 to 10 inclusive.

I claim as my invention:

35. 1. A shoe tree comprising a hollow curved toe portion of bent thin material of high resilience and high strength in proportion to its weight, said toe portion being open at its bottom, a resilient shank extending rearwardly from the toe 40 portion being integral therewith, and a channel interrupted by openings, extending along the shank substantially on the middle line thereof the stock from which said openings were formed in said channel being depressed and camming 45 surfaces formed on the ends of said depressions, some of which surfaces bear against each other when the shank is depressed during use of the tree.

2. A shoe tree according to claim 1 in which 50 the channel or rib extends through both the shank and the toe portion said channel gradually increasing in depth toward the rear of the shank whereby to provide a strong extending action to a shoe.

55. 3. A shoe tree formable by pressure from sheet

stock which comprises a toe portion open at the bottom, a channeled shank extending rearwardly from the highest point of said toe portion, a curled portion on the extreme rear end of said shank and a plurality of intermittently depressed portions extending downwardly from the middle line of said channel, said depressed portions having square ends whereby to provide bearing surfaces between certain of said depressed portions when said shank is depressed to extend a shoe.
